R. V. L. HARTLEY

SYSTEM OF CARRIER WAVE SIGNALING

Filed Oct. 11, 1920

Inventor:
Ralph V. L. Hartley

by C. A. Sprague. Atty.

UNITED STATES PATENT OFFICE.

RALPH V. L. HARTLEY, OF EAST ORANGE, NEW JERSEY, ASSIGNOR TO WESTERN ELECTRIC COMPANY, INCORPORATED, OF NEW YORK, N. Y., A CORPORATION OF NEW YORK.

SYSTEM OF CARRIER-WAVE SIGNALING.

Application filed October 11, 1920. Serial No. 416,058.

To all whom it may concern:

- Be it known that I, RALPH V. L. HARTLEY, a citizen of the United States of America, residing at East Orange, in the county of Essex, State of New Jersey, have invented 5 certain new and useful Improvements in Systems of Carrier-Wave Signaling, of which the following is a full, clear, concise, and exact description.
- 10 This invention relates to signaling systems employing carrier wave transmission and particularly to such a system wherein the carrier wave is normally impressed upon the transmission medium except during such time as it may be desired to operate a signal.
- An object of the invention is to provide 15 a simple signaling arrangement for use in combination with a telephone system wherein carrier currents and ordinary voice frequency currents are transmitted by means of a common medium, which may be a common transmission line. Another object of the invention is to provide a signaling arrangement of the type just mentioned which will 20 be operative over any length of transmission medium or common line used for telephonic purposes. Still another object of the invention is to make use of the apparatus used for speech transmission to also operate 25 signaling apparatus.
- A further object of the invention is to so arrange the apparatus of the system that each unit may function at substantially a maximum efficiency.
- 30 These objects are attained in a carrier current telephone system wherein a plurality of carrier current transmitting and receiving stations are connected to a common transmission medium and wherein carrier waves of distinctive frequencies are normally supplied by the transmitting stations for 35 reception at cooperating receiving stations, by providing a signal at each cooperating receiving station responsive upon the withdrawal 40 from the transmission medium at the transmitting station of the normally supplied oscillations. For speech transmission the normally supplied carrier wave is modulated in accordance with voice frequency 45 currents. Since the carrier wave is normally supplied to the transmission medium for speech transmission, a simple method of signaling is provided by this invention which is operative over any distances used for 50 speech transmission and which can employ 55
- for signaling purposes, apparatus which is efficient both for speech transmission and signaling.
- At the cooperating receiving station the modulated and unmodulated carrier waves 60 are translated by the detector into voice frequency current for speech transmission and into unidirectional current for signaling purposes. According to this invention separate circuits are provided at this point, one for speech transmission and another for signaling purposes. In each of these circuits apparatus most efficient for its purpose may be used.
- The invention in one embodiment is shown 70 in the accompanying drawing, and the following description thereof will more clearly show how the above objects have been accomplished. It is to be understood that other organizations of apparatus may be 75 used to embody the invention.
- Referring now to the drawing line ML is a common transmission line for carrier telephone currents, ordinary speech currents, signaling currents and other currents for 80 which it may be adapted. For the purpose of description, three lines L¹, L² and L³ terminating at one end in ordinary telephone stations X, Y and Z respectively are shown connected to the common line ML, through 85 suitable apparatus. Stations X, Y and Z may be subscribers' stations or ordinary telephone central offices. Lines L¹ and L² are adapted to transmit intelligence over the common line ML by means of high frequency 90 carrier currents through carrier channels 1 and 2, while line L³ is adapted to employ currents of voice frequency for telephone transmission.
- Line L³ is associated with the common 95 line ML through a filter LPF of the type described in Patents Nos. 1,227,113 and 1,227,114 to G. A. Campbell, dated May 22, 1917. This filter is of the low pass type and is adapted to suppress currents having 100 frequencies above the highest essential frequency of voice currents, and to transmit with substantially negligible attenuation currents of the highest essential voice frequency and of all lower frequencies. The carrier 105 channels 1 and 2 are associated with the common line ML by means of another filter HPF of the Campbell type known as a high pass filter which is adapted to pass desired currents having frequencies above the voice 110

range and to suppress all those having frequencies within the essential voice range and below. Carrier channels 1 and 2 are substantially alike except for differences in the physical constants of some of the apparatus necessitated by the use of carrier currents of different frequencies for transmission purposes.

The carrier current frequencies preferably employed are those above the essential voice frequencies. Such frequencies will herein-after be spoken of as high frequencies or high frequency oscillations.

A description of the apparatus used in channel 1 will now be given. The three winding coil LFH¹, which will hereinafter be called the low frequency hybrid coil, is used to connect the low frequency line L¹ with the transmitting circuit T¹ and the receiving circuit R¹ of channel 1. The three winding coil HFH which will hereinafter be called the high frequency hybrid coil is used to connect the transmitting circuit T¹ and the receiving circuit R¹ of channel 1 with the common line ML. Associated with these three winding coils LFH¹ and HFH are a low frequency balancing network N¹ and a high frequency balancing network NET, respectively. The network N¹ balances the low frequency line L¹, while the network NET balances the high frequency characteristics of the common line ML and the filter HPF and LPF. In the transmitting circuit T¹ there is a modulator M¹ supplied with carrier currents by the oscillator O¹. A band filter MF¹ of the Campbell type, adapted to pass currents of the carrier frequency supplied by the oscillator O¹ both unmodulated and modulated by currents of voice frequency, is connected between the modulator M¹ and the high frequency hybrid coil HFH. In the receiver circuit R¹ is a thermionic detector D¹ adapted to translate into speech currents, the unmodulated and modulated carrier currents received over common line ML from a cooperating distant station (not shown). These detected voice currents are impressed upon the low frequency line L¹ through the voice frequency transformer 10 and the low frequency hybrid coil LFH¹. Band filter DF¹, connected in the receiver circuit R¹ is of the Campbell type and is adapted to pass modulated and unmodulated carrier currents of the frequency transmitted by the distant co-operating station for reception by the detector D¹. Amplifier A¹ is inserted between the detector D¹ and the band filter DF¹ in order to increase the intensity of the incoming currents.

Since the apparatus associated with channel 2 is substantially the same as that of channel 1, a detailed description thereof is not necessary.

In order that an operator on line L¹ may

get the attention of a cooperating operator at a distant station or may herself be signaled by the distant operator, relays 3, 4 and 5 in the transmitting circuit T¹, and 6 and 7 in the receiving circuit R¹ are used. Relay 3 is responsive to ringing current from line L¹.

The impedance of relay 3 to currents of voice frequency is very large and, therefore, although it is connected directly across the low frequency line L¹ it does not act as a short circuit to voice frequency currents. Relay 4 is adapted to short-circuit the input of the modulator M¹ during the receipt of signals from the distant operator. Relay 5 is adapted to short-circuit the input of the modulator M¹ while signals are being transmitted to the distant operator. Relay 6 is conductively connected in the output of the detector D¹, being normally energized by unmodulated carrier current rectified by the detector D¹. Relay 7 which is controlled by relay 6 is adapted to disconnect the line L¹ from the carrier apparatus and to impress low frequency ringing current thereon to signal the operator whose terminal apparatus (not shown) is associated with the low frequency line L¹. Battery 8 supplies the space current for the detector D¹ and is connected in series with the relay 6 and a retardation coil 9. This retardation coil 9 offers a high impedance to currents of voice frequency and, so prevents the short circuiting of transformer 10, which transformer efficiently passes voice currents from the detector D¹ to the low frequency hybrid coil LFH¹. This retardation coil on the other hand furnishes a path of relatively low resistance to the rectified current from detector D¹ to energized the signal control relay 6.

The detector D¹ is of the three electrode thermionic vacuum tube type, comprising a hot cathode, an anode or plate and an impedance varying element or grid. The amount of space current which flows in such a device is dependent upon the potential of the grid, which potential in turn is controlled by the varying potential of the carrier wave. Relay 6 is, therefore, made marginal in its operation, that is it is not operated by the normal value of the space current which flows when no carrier waves are being received, but is operated by the increased space current which flows upon the receipt of carrier waves.

The signaling apparatus and relays of channel 2 are similar to those of channel 1 and need not be further described.

It is to be understood that at the distant end of the common line ML there is located another terminal station similar to the station shown in the drawing, comprising carrier channels cooperating with channels 1 and 2 and a low frequency line cooperating with line L¹.

The operation of the system is as follows:

The oscillator O^1 being normally connected to the modulator M^1 and operative, sends out a continuous train of waves of carrier frequency through the band filter MF^1 , the high frequency hybrid coil HFH , the high pass filter HPF and the common line ML to a cooperating distant station, (not shown).

10 Considering now for purposes of description that channel 1 is the receiving station, this train of waves is received from the common line ML through the high pass filter HPF , the high frequency hybrid coil HFH , the band filter DF^1 , the amplifier A^1 and the detector D^1 . The alternating current of carrier frequency is translated into uni-directional current which passes through the relay 6 to cause its energization.

20 Assuming now that the calling operator at station X on line L^1 desires to signal the distant operator, she will impress on the line L^1 by means of well-known apparatus (not shown) ringing current which passes over line L^1 through the back contacts (normally closed) of relay 7 to ringing responsive relay 3. The operation of relay 3 short-circuits the output of oscillator O^1 by connecting one terminal of the oscillator to ground through the normally open front contact (now closed) of relay 3, the other terminal of the oscillator being continuously connected to ground. The train of waves of carrier frequency impressed upon the common line ML will thereby be interrupted.

30 The operation of relay 3 also causes the operation of relay 5, which receives current from battery 12 when the normally open front contact of relay 3 is closed. The operation of relay 5 disconnects the modulator M^1 from the line L^1 at its normally closed back contacts and short circuits the modulator input at its front contacts to prevent it from functioning in any way whatever.

40 The effect of this interruption at the distant station will now be described in connection with the apparatus of channel 1.

50 Since no energy is being received from the common line M^1 by the detector D^1 , relay 6 will be deenergized. The deenergization of relay 6 will cause the operation of relays 7 and 4, which are connected in series with the battery 12, by closing a path to ground through its back contact. The operation of relay 7 disconnects the line L^1 from channel 1 at its normally closed back contacts (now open) and connects low frequency signaling current source 13 to the line L^1 , through its front contacts now closed. Such signaling current will operate signaling apparatus at station X to notify the operator that her attention is desired.

60 65 The operation of relay 4 above mentioned

disconnects the low frequency hybrid coil LFH^1 from the modulator at its normally closed back contacts (now open) and through its now closed front contacts, short-circuits the input of the modulator to prevent its so-called "singing" due to the unbalancing of the low frequency hybrid coil LFH^1 when the line L^1 is disconnected at the normally closed back contacts of relay 7.

70 75 Signaling over channel 2 with its cooperating distant channel may be carried on in a similar way. Additional channels may also be employed and similarly operated.

80 In the foregoing it has been noted that this invention is applicable to long distance telephone transmission lines whose length is limited only by the distance over which transmission by carrier currents can be accomplished. It is especially applicable when such lines are fifty miles or more in 85 length. It is to be understood that a line of this length is a long transmission line.

90 It should be noted that this invention makes use of the rectifying characteristics of the detectors to provide a very satisfactory method of operating a signal control relay such as relay 6 without in any way interfering with the efficiency of its operation as a translating device to receive from a common line carrier currents modulated 95 in accordance with voice frequency currents and after reception and translation to transmit the voice frequency currents to a terminal line such as L^1 .

100 It is recognized in the art that if a simple transformer such as transformer 10, is designed to most efficiently transmit currents of voice frequency, it will not be efficient to transmit currents of lower frequencies, say 105 below 200 cycles per second, such as are used in telephone signaling. In the carrier systems disclosed heretofore a single transformer has been used to transmit currents of both frequencies and a lowered efficiency 110 for each or more expensive apparatus has necessarily had to be accepted. This invention provides a system, wherein the signaling currents do not traverse the transformer, which can therefore be of simple 115 design, but still designed to operate most efficiently to transmit currents of voice frequency. At the same time it provides a simple signaling system by recognizing the adaptability and making use of characteristics of the telephone transmission apparatus 120 in a novel manner.

125 It should also be noted that this system is adapted to operate over any length of line used for carrier current telephone purposes. The source of the carrier current wave for any given channel is located at the transmitting station of that channel. The removal of the carrier wave for signaling purposes is accomplished likewise at that station and its effective removal is there- 130

fore independent of the length of the common line.

While a particular embodiment of the invention has been shown in the drawing, it is clearly not limited to that particular disclosure. The scope of the invention is defined by the accompanying claims.

What is claimed is:

1. A carrier transmission line, an oscillator for normally supplying unmodulated oscillations thereto, a modulator between said oscillator and said line, means for impressing speech currents upon said modulator to modulate said oscillations, a low frequency terminal circuit, means responsive to such modulated oscillations to transmit speech currents over said low frequency circuit, and means responsive to the withdrawal of the unmodulated oscillations from said transmission line to transmit a call signal over said low frequency circuit.

2. A carrier transmission line, an oscillator for normally supplying unmodulated oscillations thereto, a modulator between said oscillator and said line, means for impressing speech currents upon said modulator to modulate said oscillations, means for withdrawing said oscillations from said line, and means for producing a call signal during the interval when the unmodulated oscillations are withdrawn from said line.

3. In a carrier wave signaling system, a transmission line, an oscillator connected thereto, means responsive to low frequency signaling currents for short-circuiting said oscillator, a source of low frequency signaling currents, and signaling means controlled by oscillations from said oscillator.

4. In a carrier signaling system, a transmission line, a plurality of cooperating terminal stations connected thereto, a source of high frequency oscillations at one of said stations, a relay adapted to short-circuit said oscillator upon the receipt of low frequency signaling currents, a source of low frequency signaling currents, means at a cooperating station for translating oscillating current from said source of oscillations into uni-directional current, and means energized by said uni-directional current to prevent the operation of a signal at said cooperating station.

5. In a carrier signaling system, a transmission line, a plurality of cooperating terminal stations, a modulator at one of said stations, an oscillator supplying current to said modulator, a low frequency line at one of said stations, a relay operated by signaling current from said line to short-circuit said oscillator, a detector at another of said stations, a signal control relay connected in the output circuit of said detector responsive to uni-directional current from said detector

and a voice frequency transformer also connected in the output circuit of said detector, 65 and a second relay energized upon the de-energization of said signal control relay to connect signaling current to said line at said cooperating station.

6. A carrier wave system having a receiving channel comprising an electron discharge detector, said detector having two output circuits, a low frequency line associated with one of said circuits to receive speech currents from said detector when the 75 detector receives speech modulated carrier current, and a signal associated with the other of said circuits and operative in response to the application and the withdrawal of carrier current on the input circuit of 80 said detector.

7. In a carrier wave signaling system, a transmission line, an oscillator connected thereto, means responsive to trains of low frequency signaling waves to withdraw oscillations produced by said oscillator from the line throughout the duration of each of said trains, a source of low frequency signal waves, means for impressing trains 90 of waves from said source upon said responsive means, and signaling means controlled by oscillations from said oscillator.

8. A carrier wave system having a receiving channel comprising an electron discharge detector, said detector having two 95 output circuits, a low frequency line, a simple transformer primarily efficient for the transmission of speech current for associating said low frequency line with one of said circuits to transfer speech currents to said line when the detector receives speech modulated carrier current, and a signal associated with the other of said circuits and operative in response to the application and withdrawal of carrier current on the input circuit 100 of said detector.

9. A transmission line, means at one station thereon for supplying high frequency oscillations to said line, means for modulating said oscillations at times in accordance 110 with low frequency waves, a three element electric discharge device at another station on said line having its input circuit connected to said line, said discharge device having two output circuits, means associated 115 with one of said output circuits for giving an indication of the presence or absence of high frequency oscillations on said line, and means associated with the other output circuit for giving an indication when said oscillations are modulated in accordance with low frequency waves.

In witness whereof, I hereunto subscribe my name this 7th day of October, A. D. 120 1920.

RALPH V. L. HARTLEY.
